UNITED STATES PATENT OFFICE.

THOMAS S. EVANS, OF ST. LOUIS, MISSOURI, ASSIGNOR TO THE JACKES-EVANS MANUFACTURING COMPANY, OF SAME PLACE.

DESIGN FOR A CURRYCOMB.

SPECIFICATION forming part of Design No. 30,365, dated March 21, 1899.

Application filed February 17, 1899. Serial No. 706,290. Term of patent 14 years.

To all whom it may concern:

Be it known that I, THOMAS S. EVANS, a citizen of the United States, residing at the city of St. Louis, in the State of Missouri, have invented and produced a new and original Design for Currycombs, of which the following is a specification, reference being had to the accompanying drawing, forming part thereof.

The drawing is a perspective view of a currycomb, showing my new design.

1 represents a series of ribs having depending flanges 2, with notched or serrated lower edges. The ribs are connected by flat end pieces 3.

15 The leading feature of my design consists in a bar 4, surmounting the ribs and extending transversely of the length of the ribs.

The bar has a vertical bend 5, a horizontal bend 6, and a return-bend 7, the end of the bar meeting the body at the horizontal bend. 20 Surmounting the front rib 1 and extending in the direction of its length is a bar 8, the ends of which extend beyond the rib and the central part of which has a bulge 9, beneath which appears the end of the bar 4. 25

Having described my invention, what I claim as new, and desire to secure by Letters Patent, is—

The design for a currycomb, as herein shown and described.

THO. S. EVANS.

In presence of—

E. S. KNIGHT,
G. A. TAUBERSCHMIDT.
